ROTATABLLE CARD FILE

Alban R. Adkerson, Jr., 3627 Cedarhurst, Dallas, Tex.

Filed Jan. 8, 1965, Ser. No. 83,364

Term of patent 3½ years

(Cl. D33—3)

Fig. 1

Fig. 2

Fig. 3

FIGURE 1 is a front elevational view of a rotatable card file showing my design.

FIGURE 2 is a side elevational view of my new design.

FIGURE 3 is a plan view of my new design.

The faces of the file not shown are the same in appearance as the faces shown.

I claim:

The ornamental design for a rotatable card file, as shown and described.
